CONVEYER TRACK SWITCH

Frank J. Henderson, Detroit, Mich., assignor to
 Jervis B. Webb Company, Detroit, Mich., a corporation of Michigan

Application March 2, 1946, Serial No. 651,519

5 Claims. (Cl. 104—102)

1

This invention relates to trolley conveyor lines and has for its principal object to provide an improved manually operable conveyor track switch.

Track switches of the general type disclosed herein are used extensively in conveyor systems having a main conveyor line and various branch lines. The conveyor track is normally of the "I" beam or double channel type. Load supporting brackets provided with trolley wheels run along such track and switches are provided where the branch lines meet the main lines. The switches are generally provided with two or more short sections of conveyor track mounted on a movable framework and each is formed to connect the entrance track with a particular exit track where the movable framework is in a corresponding position.

One of the principal objects of the present invention is to provide a mechanism for normally locking the movable switch tracks in any one of the switch positions with means manually operable from a convenient floor level to release the locking mechanism for movement of the switch tracks to another position.

Another object of this invention is to provide a means for simultaneously releasing the locking mechanism and imparting movement to the switch tracks in either direction with a single hand movement.

A further object of the invention is to provide automatic means for stopping and locking the switch tracks in a new position after they have been released and started in motion.

Still another object of the invention is to provide a track member in the fixed frame formed from a single piece of sheet metal that will support, and guide, wheels mounted on the movable frame, as well as to serve as a supporting surface for the entrance and exit tracks and a supporting surface for the locking means.

These and other objects of the invention will appear more clearly from the following detailed description of a particular embodiment of the invention and from an examination of the drawings forming a part hereof and wherein,

Fig. 1 is a plan view of the track switch showing entrance and exit tracks mounted on a fixed frame and switch tracks mounted on a movable frame with locking means corresponding to each position.

Fig. 2 is a fragmentary end elevation of the switch taken along the line 2—2 of Fig. 1 with the conveyor tracks omitted.

Fig. 3 is a sectional view taken along the line 3—3 of Fig. 1.

2

Fig. 4 is an enlarged view of the locking mechanism shown in Fig. 1.

Fig. 5 is a sectional view of the locking mechanism taken along the line 5—5 of Fig. 4.

Fig. 6 is a sectional view taken along the line 6—6 of Fig. 4 showing the pulley housing mounted to the movable frame at one end.

Fig. 7 is a sectional view taken along the line 7—7 of Fig. 6 showing the pulley housing mounted at the other end of the movable frame with the handle extending down.

Fig. 8 is an end elevation of the conveyor track which is comprised of two opposed "C" channel members.

15 Referring to Fig. 1, a fixed frame is formed by two end members 10 and two side members 11a and 11b. The conveyor track 12 comprising two opposed channel members is mounted on the lower surface of the side member 11a. Conveyor tracks 13, 14 and 15 are mounted on the lower surface of the other side member 11b. The track 12 may be referred to as an entrance track and tracks 13, 14 and 15 as exit tracks although travel can be in either direction.

25 As illustrated in Figures 1 and 2, a movable framework, comprising two end members 16, two side members 17a and 17b, and four wheels 18 mounted on the movable frame by bracket members 19, carries three switch tracks 20, 21 and 22.

30 As shown in Figure 1 switch track 21 is in line with entrance track 12 and exit track 14. By moving the movable frame to the right, switch track 20 would connect entrance track 12 with exit track 13 or by moving it to the left, switch track 22 would connect entrance track 12 with exit track 15. Blocks 23, 24 and 25 are mounted on the fixed frame member 11b. Bellcrank latching members for engaging these blocks are also mounted on the movable frame as shown in Figures 1 and 3. Each of the bellcrank members has a longitudinally extending leg 26a and 26b respectively and each has a transversely extending leg 27a and 27b swively mounted to the movable frame by means of a bolt 29 passing through a bracket member 30 and the bellcrank journal 31.

35 40 45 Each of the ends of the bellcrank members 27a and 27b has a tongue 32a and 32b for engaging the blocks 23, 24 or 25 when the movable frame is in each respective switch position. A spring 33 is mounted under tension between the bellcrank legs 26a and 26b normally urging the bellcrank legs 27a and 27b into locking position. Pulley lines 34a and 34b are also attached to the upper ends of the bellcrank legs 26a and 26b, respectively, on the opposite sides of the spring 33.

46 50 55 Pulley line 34a runs over a pulley 36 to a handle. Pulley line 34b runs over a pulley 36 to a handle.

37. Pulley line 34b passes over pulleys 38 and 39 to handle 40.

With the track switch in central position as shown in Figure 1, it may be moved to the right by pulling on handle 37 or to the left by pulling on handle 40. By pulling on handle 37, tension in pulley line 34a acts against the spring 33 causing the bellcrank leg 26a to move to the right and the bellcrank leg 27a to move upwards out of locking position. At the same time, the force pulling bellcrank leg 26a to the right is transmitted through the bellcrank journal 31 to the bolt 29, the bracket 30 and the movable frame member 17, thereby imparting motion to the movable frame in a direction necessary to move track switch 20 into alignment with entrance track 12 and exit track 13. As soon as such motion is started and sufficient momentum given the movable frame to carry it into the new switch position, the handle may be released. The spring 33 again urges bellcrank leg 26a to the left and bellcrank leg 27a downwards into locking position. As the switch moves to the right, the tapered edge 35b will come into contact with the edge of the block 25 and the cam action therebetween will cause the bellcrank leg 27b to raise up in order to pass over the block 25. When the tongue 32b of the leg 27b passes over the far edge of block 25, the spring 33 will cause it to drop down into locking position. If it were next desired to move switch track 22 into alignment with entrance track 12 and exit track 15, handle 40 would be pulled creating a tension in pulley line 34b acting against spring 33 causing bellcrank leg 26b to move to the left and bellcrank leg 27b to move up out of locking engagement. At the same time, movement to the left would be imparted to the movable frame. In order for the movable frame to pass the central switch position, tension on the pulley line 34b is continuously applied until the tongue 32b of bellcrank leg 27b has passed the engaging edge of block 24 after which time tension may be released and the switch will continue in motion until the tongue 32b comes into locking engagement with block 23.

Thus, it is seen that with a single hand motion from a convenient floor level, simultaneous release of the latching mechanism, and movement of the switch to any new desired position may be accomplished.

While the above description and drawings relate to a particular embodiment of the present invention, it will be readily understood that numerous changes in the detailed construction could be made without departing from the spirit of the invention as described in the following claims.

I claim:

1. In combination with a trolley conveyor having a multiple track switch comprising a fixed frame mounting a plurality of stationary tracks and a movable frame mounting a plurality of switch tracks for selectively connecting alternate pairs of said tracks, and means for positively locating said movable frame in any of the positions required for connecting said tracks, said means comprising a block mounted on said fixed frame for each switch position, a latch mechanism mounted on the movable frame for alternately engaging each of said locating blocks, means for normally urging said latch mechanism into locking engagement, and selective means for simultaneously releasing said latch mechanism and imparting motion to said movable frame in either direction manually operable

70

75

at a convenient floor level by a single hand movement, said latch mechanism comprising a pair of bellcrank members pivotally mounted on said movable frame in spaced and opposed relationship so that a leg of each bellcrank member may overlie a single locating block when the movable frame is in a given switch position, the end of each of said legs being provided with a projecting surface for engaging said block thereby retaining said movable frame against movement in either direction while said mechanism is in locking engagement, said projecting surface being adapted to override said block upon release actuation of said latch mechanism.

2. In combination with a trolley conveyor having a multiple track switch comprising a fixed frame mounting a plurality of stationary tracks and a movable frame mounting a plurality of switch tracks for selectively connecting alternate pairs of said tracks, and means for positively locating said movable frame in any of the positions required for connecting said tracks, said means comprising a block mounted on said fixed frame for each switch position, a latch mechanism mounted on the movable frame for alternately engaging each of said locating blocks, means for normally urging said latch mechanism into locking engagement, and selective means for simultaneously releasing said latch mechanism and imparting motion to said movable frame in either direction manually operable at a convenient floor level by a single hand movement, said latch mechanism comprising a pair of bellcrank members pivotally mounted on said movable frame in spaced and opposed relationship so that a leg of each bellcrank member may overlie a single locating block when the movable frame is in a given switch position, the end of each of said legs being provided with a projecting surface for engaging said block thereby retaining said movable frame against movement in either direction while said mechanism is in locking engagement, and the end of each of said legs being also provided with a tapered surface which when brought into contact with a locating block tends to raise the leg for passage over the block.

3. In combination with a trolley conveyor having a multiple track switch comprising a fixed frame mounting a plurality of stationary tracks and a movable frame mounting a plurality of switch tracks for selectively connecting alternate pairs of said tracks, and means for positively locating said movable frame in any of the positions required for connecting said tracks, said means comprising a block mounted on said fixed frame for each switch position, a latch mechanism mounted on the movable frame for alternately engaging each of said locating blocks, means for normally urging said latch mechanism into locking engagement, and selective means for simultaneously releasing said latch mechanism and imparting motion to said movable frame in either direction manually operable at a convenient floor level by a single hand movement, said latch mechanism comprising a pair of bellcrank members pivotally mounted on said movable frame in spaced and opposed relationship so that one leg of each bellcrank member may overlie a single locating block when the movable frame is in a given switch position, the end of each of said legs being provided with a projecting surface for engaging said block thereby retaining said movable frame against movement in either direction while said mechanism is in locking engagement, said means normally urging said latch mechanism into locking engagement.

gagement comprising a spring mounted under tension between the other legs of said bellcrank members, said projecting surface being adapted to override said block upon release actuation of said latch mechanism.

4. In combination with a trolley conveyor having a multiple track switch comprising a fixed frame mounting a plurality of stationary tracks and a movable frame mounting a plurality of switch tracks for selectively connecting alternate pairs of said tracks, and means for positively locating said movable frame in any of the positions required for connecting said tracks, said means comprising a block mounted on said fixed frame for each switch position, a latch mechanism mounted on the movable frame for alternately engaging each of said locating blocks, means for normally urging said latch mechanism into locking engagement, and selective means for simultaneously releasing said latch mechanism and imparting motion to said movable frame in either direction manually operable at a convenient floor level by a single hand movement, said latch mechanism comprising a pair of bellcrank members pivotally mounted on said movable frame in spaced and opposed relationship so that one leg of each bellcrank member may overlie a single locating block when the movable frame is in a given switch position, the end of each of said legs being provided with a projecting surface for engaging said block thereby retaining said movable frame against movement in either direction while said mechanism is in locking engagement, the end of each of said legs also being provided with a tapered surface adapted to effect an overriding of said block upon movement toward a locking position, said means normally urging said latch mechanism into locking engagement comprising a spring mounted under tension between the other legs of said bellcrank members, said means for releasing said latch mechanism and imparting motion to said movable frame comprising a flexible pulling member attached to each of the last mentioned legs and passing over guide pulleys in a manner whereby tension applied to either of said pulling members will act against said spring actuating the bellcrank member to which it is attached in a direction causing the engaging surface of said member to be raised to a position for overriding said block while simultaneously imparting motion to said movable frame in either direction.

5. In combination with a trolley conveyor having a multiple track switch comprising a fixed frame mounting a plurality of stationary tracks

and a movable frame mounting a plurality of switch tracks for selectively connecting alternate pairs of said tracks, and means for positively locating said movable frame in any of the positions required for connecting said tracks, said means comprising a block mounted on said fixed frame for each switch position, a latch mechanism mounted on the movable frame for alternately engaging each of said locating blocks, means for normally urging said latch mechanism into locking engagement, and selective means for simultaneously releasing said latch mechanism and imparting motion to said movable frame in either direction manually operable at a convenient floor level by a single hand movement, said latch mechanism comprising a pair of bellcrank members pivotally mounted on said movable frame in spaced and opposed relationship so that one leg of each bellcrank member may overlie a single locating block when the movable frame is in a given switch position, the end of each of said legs being provided with a projecting surface for engaging said block thereby retaining said movable frame against movement in either direction while said mechanism is in locking engagement, and the end of said legs being also provided with a tapered surface which when brought into contact with a locating block tends to raise the leg for passage over the block, said means normally urging said latch mechanism into locking engagement comprising a spring mounted under tension between the other legs of said bellcrank members, said means for releasing said latch mechanism and imparting motion to said movable frame comprising flexible pulling members attached to each of the last mentioned legs and passing over guide pulleys in a manner whereby tension applied to either of said pulling members will act against said spring actuating the bellcrank member to which it is attached in a direction causing the engaging surface of said member to be raised out of locking position while simultaneously imparting motion to said movable frame in either direction.
